UNITED STATES PATENT OFFICE.

DUDLEY S. SEYMOUR, OF OAK PARK, ILLINOIS, ASSIGNOR TO UNION SPECIAL MACHINE COMPANY, OF CHICAGO, ILLINOIS, A CORPORATION OF ILLINOIS.

FEEDING MECHANISM FOR SEWING-MACHINES.

1,297,920.

Specification of Letters Patent. Patented Mar. 18, 1919.

Application filed March 10, 1916. Serial No. 83,298.

To all whom it may concern:

Be it known that I, DUDLEY S. SEYMOUR, a citizen of the United States, residing at Oak Park, in the county of Cook, State of Illinois, have invented certain new and useful Improvements in Feeding Mechanism for Sewing-Machines, of which the following is a description, reference being had to the accompanying drawing and to the figures of reference marked thereon:

The invention relates to new and useful improvements in feeding mechanisms for sewing machines and more particularly to a feeding mechanism for feeding the work along a suspended work supporting arm which is arranged at an angle to the vertical plane of the overhanging arm of the machine.

An object of the invention is to provide a feeding mechanism for a sewing machine of the above character wherein the feeding device may be positively operated from a main rotating shaft located in a horizontal arm from the outer end of which the work supporting arm is suspended.

A further object of the invention is to provide a feeding mechanism of the above character with an auxiliary feeding device and with means located in the work supporting arm for giving a differential movement thereto.

These and other objects will in part be obvious and will in part be hereinafter more fully disclosed.

In the drawings, which show by way of illustration, one embodiment of the invention,

Figure 1 is a side view of a sewing machine embodying my invention and with parts broken away to show a portion of the feeding mechanism, also showing the needle bar operating mechanism;

Fig. 2 is a view partly in front elevation and partly in section of the standard and arm supported thereby;

Fig. 3 is a longitudinal sectional view through the work supporting arm and supporting post therefor;

Fig. 4 is a horizontal sectional view through the upper part of the work supporting arm showing the feeding mechanism therein, in plan;

Fig. 5 is a detail in vertical section showing the controlling mechanism for varying the movements of the auxiliary feed bar;

Fig. 6 is a sectional view on the line 6—6 of Fig. 5;

Fig. 7 is a view on the line 7—7 of Fig. 5; and

Fig. 8 is a perspective view of the fulcrum 60 pin for the feed bar;

As illustrated in the drawings, the invention is applied to a sewing machine having a standard 1 with a supporting base 2, whereby it may be secured to the table. 65 Mounted on the standard at the upper end thereof and projecting laterally therefrom is an overhanging arm 3 in which is mounted a shaft 4. Projecting forwardly from the standard 1 is an arm 5 which supports a 70 horizontal arm 6. The horizontal arm 6 is substantially parallel with the overhanging arm 3 and carries at its outer end a depending post 7. At the lower end of the post 7 is the work supporting arm 8 which extends 75 toward the overhanging arm and has its free end terminating underneath the free end of the overhanging arm. This work supporting arm is, therefore, arranged at an angle to the vertical plane containing the 80 longitudinal center of the overhanging arm, that is, the plane of the overhanging arm.

Mounted in the horizontal arm 6 is the main shaft 9, which extends through the arm 5. Said main shaft is journaled in the bearing 10 at one end thereof and in the bearings 11 and 12 adjacent the other end thereof. The shaft is driven by a belt wheel 13 which is located on the outer end thereof. The shaft 9 intermediate its bearings 11 and 12 90 is formed with a crank 14 and a pitman 15 co-operating therewith is connected to a depending arm 16 on the shaft 4 in the overhanging arm 3 and serves as a means for oscillating the same. 95

Mounted in the forward end of the overhanging arm is a needle bar 17 carrying needles 18. On the adjacent end of the shaft 4 is an arm 19 which is connected by a link 20 to a collar on the needle bar so that the 100 oscillations of the shaft 4 will be imparted to the needle bar.

The material is held on the work supporting arm 8 by a presser foot 21 which is fixed to the lower end of a presser bar 22. Co-operating with the needle beneath the work support are loopers 23, which are secured to the looper carrier 24 mounted on the outer end of the looper supporting shaft 25. This looper supporting shaft is in turn mounted 110

- in suitable bearings 26 and 27 so that it may oscillate and move endwise in the bearings. The looper shaft is oscillated by a train of mechanism connected to the main shaft 9.
- 5 Near the outer end of the shaft is an eccentric 28. An eccentric strap 29 coöperates therewith and is connected at its lower end to an arm 30 projecting from a cross shaft 31. Said cross shaft is provided with a second arm 32 carrying a ball stud at its outer end. A collar 33 is fixed to the looper supporting shaft 25 and is formed with an arm 34. This arm carries a ball stud. A link 35 connects the ball studs on the arms 32 and 34. These ball studs permit the looper supporting shaft 25 to be moved endwise without interfering with the train of connections between the looper shaft and the cross shaft 31.
- 28 The looper supporting shaft 25 is moved endwise by a second eccentric on the main shaft 9. This eccentric coöperates with an eccentric strap 36 which is connected at its lower end to a ball stud 37 carried by an arm 38 projecting laterally from a cross shaft 39 which is journaled in suitable bearings in the work supporting arm. The cross shaft 39 is formed with a second arm 40 which is provided with a slot adapted to 25 adjustably receive and support a ball stud 41. Mounted on the looper supporting shaft 25 is a sleeve 42 which is held from endwise movement relative to the looper supporting shaft by fixed collars 43 and 44. This sleeve 35 has a downwardly depending rib 45 which extends between guides 46. This prevents oscillation of the sleeve although said sleeve may be moved lengthwise. A link 46 is connected to the sleeve at one end and at its 40 other end said link is connected to the ball stud 41 so that the oscillations of the cross shaft 29 will impart an endwise movement to the looper supporting shaft.
- 45 The feeding mechanism, as herein shown, consists of a main feed dog 47 and an auxiliary feed dog 48 which are arranged in tandem relation. These feed dogs are arranged so as to feed the material off from the end of the work supporting arm. The main feed dog 47 is carried by a feed bar 49. Said feed bar has depending bracket arms 50 which are pivoted to a sleeve 51 on the looper supporting shaft 25. Disposed within the sleeve 51 is an eccentric 52 which is fixed to said shaft. The sleeve 51 is capable of being moved endwise relative to the eccentric 52 but the rotating movement of the eccentric will raise and lower the sleeve. The feed bar 49 extends lengthwise 55 of the work supporting arm and at its rear end is fulcrumed on a pin 53. The pin 53 is mounted in suitable bearings in the work supporting arm and has a reduced central section 54. A cap plate 55 is secured to the feed bar and this cap plate is recessed, as 60 at 56^a, to form an elongated slot which receives the central section 54 of the fulcrum pin 53. This permits the feed bar to be moved endwise on the fulcrum pin and also permits the feed bar to be raised at its 65 forward end through the action of the eccentric 52, said pin serving as a fulcrum at this time.
- 65 The cross shaft 39 is provided with a third arm 56 which has the slot 57 formed 70 therein. A stud 58 is adjustably mounted in this slot. A link 59 is connected at one end to the stud 58 and at its other end to a stud 60 mounted on the end of the main feed bar 49. As the cross shaft oscillates 75, the main feed bar will be moved back and forth. As the looper supporting shaft 25 is oscillated, the eccentric 52 will raise and lower the feed dog, and these two active devices give the required movements to the 80 feed dogs. By adjusting the stud 58 in the slot 57 the throw of the feed bar and the resulting feeding movement of the feed dog may be varied.
- 85 The auxiliary feed dog 48 is carried by an auxiliary feed bar 61. The main feed bar is slotted longitudinally and the auxiliary feed bar is located therein. A screw 62 passing through a slot in the auxiliary feed dog holds the same on the auxiliary feed 90 bar. A clip 63 holds these bars in assembled relation but permits the auxiliary bar to slide freely independently of the main bar. Said feed bars will be raised and lowered simultaneously by the eccentric 52. The auxiliary feed bar is moved back and forth by a connection from the main bar which consists of the following parts:
- 95 A U-shaped lever 63 is pivotally supported in the work supporting arm and feed 100 bar and looper supporting shaft pass between the arms of this lever. The arm 64 of said U-shaped lever projects up alongside of the auxiliary feed bar and is connected to said auxiliary bar by a link 65. Said link is pivoted at 66 to the arm 64 and is pivoted at 67 to the auxiliary feed bar. The side of the main bar is cut away to permit this connection. The other arm 68 of the U-shaped lever projects up along the 105 other side of the auxiliary feed bar and is formed with a curved slot 69. A link 70 is pivoted at 71 to the main feed bar and carries a roller or stud 72 which engages the slot 69. When the link is disposed as shown 110 in Fig. 5, that is, with the roller or stud 72 at the upper end of the slot 69, the auxiliary feed bar will be moved back and forth substantially in unison with the main feed bar. In other words, the roller or stud 72 115 is substantially in alignment with the pivotal connection 66 between the link 65 and the arm 64. When this link 70, however, is shifted toward the lower end of the slot 69 then the auxiliary feed bar will be given a 120
- 125
- 130

greater throw than the main feed bar for obvious reasons.

The link 70 may be shifted by hand lever 73 which is pivoted at 74 to a suitable lug 5 on the inner face of the work supporting arm and is connected by a link 75 to said link 70. At the outer end of the lever 73 there is a hand piece 76 which extends to the outer face of the work supporting arm 10 so that the lever may be readily adjusted and this hand piece may be formed with suitable devices for holding the lever in adjusted positions.

From the above description it will be 15 apparent that I have provided a sewing machine having a suspended work supporting arm with a feeding mechanism wherein the main feed dog is positively actuated from a train of mechanism connected to the main shaft at a point directly over the work supporting arm. By this arrangement of parts the train of mechanism between the main shaft and the feed bar includes very few parts which, of course, increases the efficiency 20 of the feeding mechanism.

It is obvious that minor changes in the details of construction and arrangement of parts may be made, without departing from the spirit of the invention as set forth in the 25 appended claims.

Having thus described my invention, what I claim as new and desire to secure by Letters Patent, is:-

1. A sewing machine including in combination stitch forming mechanism, a standard, an overhanging arm, a horizontal arm carried by the standard, a main shaft located in said horizontal arm, a work supporting arm carried by said horizontal arm, a feeding device carried by said work supporting arm, means for positively actuating said feeding device from the main shaft in the horizontal arm and driving connections between the main shaft and the stitch forming mechanism.

2. A sewing machine including in combination stitch forming mechanism, a standard, an overhanging arm carried thereby, a horizontal arm carried by the standard, a main shaft located in the horizontal arm, a work supporting arm carried by said horizontal arm and extending at an angle to the vertical plane of the overhanging arm, a feeding device in said work supporting arm, a feed bar carrying said feeding device, means operated from the end of the shaft adjacent the work supporting arm for positively moving said feed bar back and forth, means operated from the end of the shaft 50 adjacent the work supporting arm for positively raising and lowering the feed bar and driving connections between said main shaft and the stitch forming mechanism.

3. A sewing machine including in combination a standard, an overhanging arm

carried thereby, a horizontal arm carried by the standard, a main shaft located in the horizontal arm, a work supporting arm carried by said horizontal arm and extending at an angle to the vertical plane of the overhanging arm, a feeding device in said work supporting arm, a feed bar carrying said feeding device, means operated from the end of the shaft adjacent the work supporting arm for positively moving said feed bar back and forth, means operated from the end of the shaft adjacent the work supporting arm for positively raising and lowering the feed bar, an auxiliary feeding device, an auxiliary feed bar carrying said auxiliary feeding device, means whereby said auxiliary feeding device is raised and lowered with the main feed bar, and means operated by the main feed bar for moving said auxiliary feed bar back and forth. 85

4. A sewing machine including in combination a standard, an overhanging arm carried thereby, a horizontal arm carried by the standard, a main shaft located in the horizontal arm, a work supporting arm carried by said horizontal arm and extending at an angle to the vertical plane of the overhanging arm, a feeding device in said work supporting arm, a feed bar carrying said feeding device, means operated from the end 90 of the shaft adjacent the work supporting arm for positively moving said feed bar back and forth, means operated from the end of the shaft adjacent the work supporting arm for positively raising and lowering the feed bar, an auxiliary feeding device, an auxiliary feed bar carrying said auxiliary feeding device, means whereby said auxiliary feeding device is raised and lowered with the main feed bar, a lever located in 95 said work supporting arm, devices connecting the lever to the auxiliary feed bar, and driving connections between the main feed bar and said auxiliary lever whereby the reciprocations of the main feed bar osculate 100 said lever.

5. A sewing machine including in combination, a standard, an overhanging arm carried thereby, a horizontal arm carried by the standard, a main shaft located in the horizontal arm, a work supporting arm carried by said horizontal arm and extending at an angle to the vertical plane of the overhanging arm, a feeding device in said work supporting arm, a feed bar carrying 115 said feeding device, means operated from the end of the shaft adjacent the work supporting arm for positively moving said feed bar back and forth, means operated from the end of the shaft adjacent the work supporting arm for positively raising and lowering the feed bar, an auxiliary feeding device, an auxiliary feed bar carrying said auxiliary feeding device, means whereby said auxiliary feeding device is raised and 120 lowered with the main feed bar, a lever located in said work supporting arm, devices connecting the lever to the auxiliary feed bar, and driving connections between the main feed bar and said auxiliary lever whereby the reciprocations of the main feed bar osculate 125 said lever.

lowered with the main feed bar, a lever located in said work supporting arm, devices connecting the lever to the auxiliary feed bar, and means for connecting the main feed bar to said lever whereby the reciprocations of the main feed bar oscillate said lever, said connection between the main feed bar and the lever being adjustable whereby the throw of the auxiliary feed bar relative to the main feed bar may be varied.

6. A sewing machine including in combination a standard, an overhanging arm carried thereby, a horizontal arm carried by the standard, a main shaft located in the horizontal arm, a work supporting arm carried by said horizontal arm and extending at an angle to the plane of the overhanging arm, a feeding device in said work supporting arm, a feed bar carrying said feeding device, means operated from the end of the shaft adjacent the work supporting arm for positively moving said feed bar back and forth and means operated from the end of the shaft adjacent the work supporting arm for positively raising and lowering the feed bar, an auxiliary feeding device, an auxiliary feed bar carrying said auxiliary feeding device, means whereby said auxiliary feeding device is raised and lowered with the main feed bar, a lever located in said work supporting arm, devices connecting the lever to the auxiliary feed bar, means for connecting the main feed bar to said lever whereby the reciprocations of the main feed bar oscillate said lever, said connection between the main feed bar and the lever being adjustable whereby the throw of the auxiliary feed bar relative to the main feed bar may be varied, and a hand lever for said adjustable connections.

7. A sewing machine including in combination a standard, a horizontal arm carried by said standard, a depending post carried by said horizontal arm, a work supporting arm mounted at the lower end of said post, a main shaft in said horizontal arm, a main feed dog in the work supporting arm, a feed bar extending lengthwise of said work supporting arm and carrying said main feed dog, a cross shaft, means operated by the main shaft for oscillating said cross shaft, a link connecting said cross shaft to the main feed bar for moving the same back and forth, and means for raising and lowering the feed bar.

8. A sewing machine including in combination a standard, a horizontal arm carried by said standard, a depending post carried by said horizontal arm, a work supporting arm mounted at the lower end of said post,

a main shaft in said horizontal arm, a main feed dog in the work supporting arm, a feed bar extending lengthwise of said work supporting arm and carrying said main feed dog, a cross shaft, means operated by the main shaft for oscillating said cross shaft, a link connecting said cross shaft to the main feed bar for moving the same back and forth, said link being adjustably connected to the cross shaft whereby the stroke of the feed bar may be varied, and means for raising and lowering the feed bar.

9. A sewing machine including in combination, a standard, a horizontal arm carried by said standard, a depending post carried by said horizontal arm, a work supporting arm mounted at the lower end of said post, a main shaft in said horizontal arm, a main feed dog in the work supporting arm, a feed bar extending lengthwise of said work supporting arm and carrying said main feed dog, a cross shaft, means operated by the main shaft for oscillating said cross shaft, a link connecting said cross shaft to the main feed bar for moving the same back and forth, said link being adjustably connected to the cross shaft whereby the stroke of the feed bar may be varied, and devices operated by said main shaft for raising and lowering the feed bar.

10. A sewing machine including in combination, a standard, a horizontal arm carried by said standard, a depending post carried by said horizontal arm, a work supporting arm mounted at the lower end of said post, a main shaft in said horizontal arm, a main feed dog in the work supporting arm, a feed bar extending lengthwise of said work supporting arm and carrying said main feed dog, a cross shaft, means operated by the main shaft for oscillating said cross shaft, a link connecting said cross shaft to the main feed bar for moving the same back and forth, said link being adjustably connected to the cross shaft whereby the stroke of the feed bar may be varied and devices operated by said main shaft for raising and lowering the feed bar, an auxiliary feed dog, a feed bar carrying said auxiliary feed dog, means for connecting the feed bars whereby they move up and down together, and devices located in said work supporting arm and connected to the main feed bar for moving the auxiliary feed bar back and forth.

In testimony whereof I affix my signature, in the presence of two witnesses.
